DUAL CONTROL SYSTEM

Peter Mostek, Independence, Ohio

Application April 30, 1954, Serial No. 426,628

1 Claim. (Cl. 307—140)

This invention relates to electrical control systems and has for its primary object the provision of electrical circuits capable of being utilized to control two separate loads totally independent of each other utilizing only one pair of conductors.

A further object of this invention resides in the provision of a dual control system for use in separately and independently operating two load devices, such as electric trains, while utilizing only a pair of conductors such as exemplified by the tracks on which the trains ride to complete the operative electrical circuits.

The invention is especially adapted for use in conjunction with toy or miniature trains so that the speed of two independent trains traveling on a single track can be separately controlled and varied.

Still further objects and features of this invention reside in the provision of a dual control system which is simple in its components, composed of readily available parts, which may be used in conjunction with various existing types of equipment, and which is comparatively inexpensive thereby permitting the wide use and distribution.

These, together with the various ancillary objects and features of the invention which will become apparent as the following description proceeds, are attained by this dual control system, various embodiments of which have been illustrated in the accompanying drawings, by way of example only, wherein:

Figure 1 is a circuit diagram of an embodiment of the invention especially adapted for use in controlling toy electric trains;

Figure 2 is a schematic diagram illustrating the principles of the invention which is adapted for use in conjunction with electric trains and which utilizes a pair of transformers; and

Figure 3 is a circuit diagram of an arrangement for turning two load devices on or off such as two electric lamps, or the like.

With continuing reference to the accompanying drawings wherein like reference numerals designate similar parts throughout the various views, and with initial attention directed to the embodiment of the invention, as is shown in Figure 1, it will be noted that this dual control system is especially adapted for use in conjunction with electric trains which are adapted to ride on track 10 formed from a middle rail 12 which is insulated from the outside rails 14. The dual control system is adapted to control two independent electric trains operated by locomotives shown schematically at 16 and 18.

The dual control system is adapted to be connected to the source of alternating current as at 20 which is connected to the primary coil 22 of a transformer generally indicated at 24 having a secondary coil 26 provided with a pair of pick-up slides 28 and 30 forwardly mounted thereon.

Connected to the slides 28 and 30 are rectifiers 32 and 34 which are of opposite polarity. The rectifiers 32 and 34 are both connected to conductor 36 which, in turn, is connected to the middle rail 12. Connected to the mid-

2

dle rail 12 are receiving rectifiers 38 and 40 which are of the same polarity as the rectifiers 32 and 34, respectively, and which are connected to the motors 44 and 46 of the locomotives 16 and 18. The motors are connected through conductors 48 and 50 to the outer rails 14 which are in effect but a single conductor. Condensers 52 and 54 are connected to the rectifiers 38 and 40 in parallel with the motors 44 and 46.

Inasmuch as the voltage picked up from the transformer secondary 26 by the slides 28 and 30 will be transmitted by the transmitting rectifiers 32 and 34 as only the positive half and the negative half respectively of the sign wave form of electrical impulse, the motors 44 and 46 will be energized by these rectified impulses. This arrangement in view of the respective polarities of the transmitting and receiving rectifiers, will not allow feed back from the respective load devices 16 and 18. In order to supply a continuous and substantially four way form of power to the motors 44 and 46, it will be seen that the condensers 52 and 54 store power when the receiving rectifiers 38 and 40 permit the transmission of power and when they prevent the other half wave of power from being delivered to the motors 44 and 46, the condensers 52 and 54 will then discharge.

Referring now to the embodiment of Figure 2, it will be noted that herein two separate transformers 60 and 62 are energized by the alternating current supply 64. Connected to the secondaries of the transformers by means of any convenient means, are the transmitting rectifiers 66 and 68 which are connected to a single conductor 70. Connected to the conductors 70 are the load devices 72 and 74 and condensers 76 and 78 are effectively arranged so as to be in parallel connection with the respective load devices 72 and 74 so that when current is permitted to flow through the receiving rectifiers 80 and 82 the condensers 76 and 78 will become charged so as to be able to deliver their stored energy to the load devices 72 and 74 when the respective rectifiers do not permit passage of electrical energy. The single line 84 interconnects the load devices with the secondaries of the transformers 60 and 62 to complete the operative electrical circuits.

In the embodiment of the invention as is shown in Figure 3, no transformers are utilized but switches 90 and 92 interconnect the dual control system with the source of alternating current. Transmitting rectifiers 94 and 96 are connected through the switches 90 and 92 to the source of alternating current and are connected by means of a single conductor 98 to the receiving rectifiers 100 and 102. The load devices 104 and 106 are connected to the rectifiers 100 and 102 and to the supply line 108. Condensers 110 and 112 are connected in parallel connection with the loads 104 and 106 so that the condensers will become charged when the rectifiers 100 and 102 are transmitting electrical power so as to assure a substantially rectified full wave of power to the load devices 104 and 106.

From the foregoing, it can be readily understood that utilizing either the slides 28 and 30, the transformers 60 and 62, or the switches 90 and 92 in the various forms of the invention, control of either one of two load devices or control of both of the load devices at the same time can be achieved. Further, since from the foregoing the construction and advantages of this invention can be readily understood, further description is believed to be unnecessary.

65 However, since numerous modifications will readily occur to those skilled in the art, after a consideration of the foregoing specification and accompanying drawings, it is not intended to limit the invention to the precise embodiments shown and described, but all suitable modifications and equivalents may be readily resorted to which fall within the scope of the appended claim.

What is claimed as new is as follows:

A control system for supplying variable amounts of electrical power to a first load device and a second load device comprising a source of alternating current, a transformer having a primary coil connected to said source of alternating current, said transformer having a secondary coil provided with a pair of pickup slides movably mounted thereon for connecting said secondary coil to said load devices to supply variable amounts of electrical power to said load devices, a first transmitting rectifier and a second transmitting rectifier each connected to one of said slides, said transmitting rectifiers being of opposite polarity and being connected to a single conductor, a first receiving rectifier and a second receiving rectifier connected to said single conductor, said first receiving

5

rectifier being connected to said first load device, said second receiving rectifier being connected to said second load device, and condensers connected to said receiving rectifiers in parallel connection with said load devices, said condensers being charged when said receiving rectifiers pass current to said load devices, said condensers discharging to provide power to said load devices when said receiving rectifiers prevent passage of current to said load devices.
